(57) **CLAIM**

The ornamental design for a pedicure basin base, as shown and described.

DESCRIPTION

FIG. 1 is an upper perspective view of the pedicure basin base according to my design.

FIG. 2 is a front elevation view thereof;

FIG. 3 is a back elevation view thereof;

FIG. 4 is a top plan view thereof;

FIG. 5 is a bottom plan view thereof;

FIG. 6 is a side elevation view thereof, an opposite side elevation view being a mirror image thereof; and,

FIG. 7 is another upper perspective view thereof, showing accessories of the pedicure basin base in broken lines.
